CLAIM

The ornamental design for a camera mount as shown and described.

DESCRIPTION

FIG. 1 is a front perspective view of a camera mount showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front perspective view thereof shown in a state of use.

The broken line portions in the drawings form no part of the claimed design.

1 Claim, 8 Drawing Sheets
